(57) **CLAIM**

The ornamental design for a tattooing apparatus, as shown and described.

DESCRIPTION

FIG. 1 illustrates a front-right side perspective view of a tattooing apparatus of the present invention.

FIG. 2 illustrates a front plane view of the tattooing apparatus of FIG. 1.

FIG. 3 illustrates a rear plane view of the tattooing apparatus of FIG. 1.

FIG. 4 illustrates a left side view of the tattooing apparatus of FIG. 1.

FIG. 5 illustrates a right side view of the tattooing apparatus of FIG. 1.

FIG. 6 illustrates a top plane view of the tattooing apparatus of FIG. 1.

FIG. 7 illustrates a bottom plane view of the tattooing apparatus of FIG. 1; and,

FIG. 8 illustrates the front-right side perspective view of the tattooing apparatus of FIG. 1 showing a needle cartridge shown in broken lines.

The broken lines illustrate environmental structure or boundaries that form no part of the claimed design.
